NORMAN R. SMITH AND PAUL A. TALBOT, OF SEATTLE, WASHINGTON, AS-SIGNORS TO SEATTLE ROTARY ENGINE COMPANY, OF SEATTLE, WASHINGTON, A CORPORATION OF WASHINGTON.

ROTARY HEAD FOR ROTARY ENGINES.

No. 833,698.

Specification of Letters Patent.

Patented Oct. 16, 1906.

Application filed December 19, 1905. Serial No. 292,489.

To all whom it may concern:

Be it known that we, NORMAN R. SMITH and PAUL A. TALBOT, citizens of the United States, and residents of the city of Seattle, in

5 the county of King and State of Washington, have invented certain new and useful Improvements in Rotary Heads for Rotary Engines, of which the following is a specification.

10 Our invention relates to improvements in the construction of the rotary head of the rotary engine shown in the patent issued October 24, 1905, to Norman R. Smith, No. 802,828.

15 The object of our invention is to improve and simplify the construction of this part of the engine. In the drawings we show this in the form which is now preferred by us.

Figure 1 is an end view of the rotary head. 20 Fig. 2 is a partial side view and partial section of the rotary head.

The general outline of the rotary head is that of a cylinder of a cross-section somewhat resembling an ellipse. This is divided on 25 planes which are substantially perpendicular to the long diameter of the ellipse into four principal parts 1, 2, 3, and 4.

One plane of division is that which includes the axis of revolution. This is indicated by 30 the line 23. The other planes lie between this and the respective ends of the long diameter. These are represented, respectively, by the lines 12 and 34. These latter lines of division are not continuous planes, but 35 each has a central section offset outwardly to the line 5.

The outer lines of division correspond, essentially, to the location of the two valves. One of these valves is shown at 10, Fig. 2, 40 and by dotted lines in Fig. 1. By dividing the head on these planes it is easy to finish the valve-seats truly.

The central line of division 23 permits of the insertion of the rock-shaft by which the 45 valves are shifted. This rock-shaft 6 is shown by dotted lines in Fig. 1 and has a central crank-arm 60, which while not exactly necessitating the central division makes it easier to insert it by reason of this division.

50 The two central parts of the head are locked together by a key device at each side of the shaft, which prevents their displacement laterally of the shaft-opening before it is placed on the shaft. We have shown this in Fig. 1 as consisting of a rib or key 30, which

has been formed integrally of the part 3, and a receiving-groove formed in the companion part 2. The key may, however, be separate from both parts.

The various parts are bound together into 60 a rigid whole by means of two straps 7, which are placed in channels recessed in the end faces of the head a short distance inward from its periphery. Each strap consists of two pieces of steel, each of which extends 65 about half the head, where they overlap each other and are secured together and drawn tight by taper keys 8. The overlapping ends of these straps and the securing-key as they would appear if seen from the side are 70 shown in Fig. 2. From this view the strap is reduced in thickness near its end and then thickened to form a hook 17. These hooks pass by each other to form an opening for the reception of the securing-key 8. The edges 75 of this key are shown as beveled or making, respectively, an acute and an obtuse angle with the sides, which tends to hold the two ends from lateral separation. As a further guard against this we have shown keys 27, 80 which fit seats formed, respectively, in the ends and in the adjacent surface of a shoulder formed in the other half of the strip.

The keys 8 are inserted in a hole which extends through the shell of the head lying outside of the groove in which the shaft is placed. Centrally of the head is an annular groove or recess 20, into which the inner ends of the keys project. This end is threaded and the keys are drawn tight by nuts thereon. This 90 annular recess opens into the interior cavity of the head, which is used to receive the exhaust-steam, and the opening 20 conducts this exhaust-steam to the exhaust-ports. The openings 30 are the steam-supply ports 95 and pass entirely through the rotary head.

Relative movement lengthwise the shaft between the parts 1 and 2 and the parts 3 and 4 is provided against by keys 15, which are embedded in each in the contact-faces outside the ends of the valves. Relative movement in the other direction is prevented by the offset between the faces 5 and 12 and also by the beveled surfaces 13, extending inwardly from the periphery of the rotary head. 105

At the ends of the long diameter of the rotary head, where contact would be made with the inclosing cylinder, we provide a groove containing a packing-strip 14, which is held out by spring or steam pressure, as desired. 110

We have shown for this purpose a spring 16, consisting of a flat bar bent into a wavy shape.

The straps 7, while apparently reduced in size where they overlap, are not really reduced below the section in the body thereof, as their width is increased in the other direction. This method of constructing and assembling the parts forming the rotary head makes it easy to finish the valve-seats and other like surfaces and makes a strong rigid structure when assembled.

Having thus described our invention, what we claim, and desire to secure by Letters Patent, is—

- 15 1. A rotary head for rotary engines divided into a plurality of fitting sections and ring-like straps peripherally clamping and securing said sections together to form the complete head.
- 20 2. A rotary head for rotary engines divided into a plurality of parts having when assembled a groove or recess in each end face extending about said face and within its periphery, and a strap in each of said grooves binding the whole together.
- 25 3. A rotary head for rotary engines divided into a plurality of parts having when assembled a groove extending just within the periphery in each end face, binding-straps in each of said grooves, and means for locking said parts to prevent sliding on their contact-surfaces.
- 30 4. A rotary head for rotary engines divided into a plurality of parts by planes extending in the same direction as the axis of rotation, said parts having communicating grooves

forming ring-like recesses in their end faces and binding-straps in said grooves.

5. A rotary head for rotary engines divided into a plurality of parts having communicating grooves, binding-straps in said grooves and keys for joining and tightening said straps. 40

6. A rotary head for rotary engines divided into a plurality of parts having communicating grooves in their end faces just within their periphery, binding-straps in said grooves and taper keys for joining and tightening said straps. 45

7. A rotary head for rotary engines, divided into a plurality of parts having communicating grooves in their end faces, and binding-straps in said grooves, said straps having overlapping ends provided with hook-like ends, and locking-keys adapted to fit between the hook-faces of the overlapping ends. 50

8. A rotary head for rotary engines, divided into a plurality of parts having communicating grooves and binding-straps in said grooves having overlapping hook-like ends, a locking-key fitting between the hook-faces of said ends and keys engaging the outer faces of said ends and the body of the straps to prevent lateral displacement. 55

In testimony whereof we have hereunto affixed our signatures, this 24th day of November, 1905, in the presence of two witnesses.

NORMAN R. SMITH.
PAUL A. TALBOT.
